UNITED STATES PATENT OFFICE.

BERNARD A. KOELLHOFFER, OF NEWARK, NEW JERSEY.

GAME.

1,349,615.

Specification of Letters Patent. Patented Aug. 17, 1920.

Application filed June 20, 1919. Serial No. 305,458.

To all whom it may concern:

Be it known that I, BERNARD A. KOELLHOFFER, a citizen of the United States, residing at Newark, in the county of Essex and 5 State of New Jersey, have invented certain new and useful Improvements in Games, of which the following is a specification.

This invention relates to game apparatus, and more particularly to a game board with 10 which game pieces may be used for playing different games.

The game board and game pieces are designed to be used particularly to play either one of two games, designated as "base ball" 15 and "catching the burglar". The board and game pieces may be employed for playing other games but the details of the two games mentioned will be set forth hereinafter in detail and an understanding of the invention 20 may be gained from the description and from a consideration of the accompanying drawings, wherein:-

Figure 1 is a plan view of the game board constructed in accordance with my invention.

Fig. 2 is a view of the vari-colored game pieces which are to be moved about the game board, and

Fig. 3 is a view of ordinary dice used in 30 playing the game.

Referring to the drawings wherein is illustrated the preferred form of my invention, in which like numerals of reference indicate like or corresponding parts throughout the several views, the board 1 is substantially square and has its surface divided into small squares or blocks colored alternately red and white. At the exact center of the board in one of the red squares, 40 is a circular spot 2 which is designated as the "pitcher's box" when playing the game of base ball. A "diamond" is inscribed on the board around the pitcher's box by the black lines 3, 4 5 and 6, and at one corner of the

45 "diamond", one of the squares is marked with a "z" to indicate the "home plate" 7. First base, second base and third base are indicated at 8, 9 and 10 by circles at the other three corners of the "diamond". The 50 foul lines, plainly marked in Fig. 1 extend parallel to two adjacent sides of the "diamond" from the home plate 7. Two players play the game of base ball, and each may be referred to as the "manager" of

a base ball team. Each person selects nine 55 games pieces of like color and each person then throws the dice to determine who shall be first at bat. The player taking the field, places his men around the field in approximately the same positions, with respect to 60 the diamond and the bases, as are assumed by the players engaged in the well known game of base ball. The players will be hereinafter designated as "managers of the teams". The manager of the team in the 65 field may place his men on any of the red squares and change their position at any time to suit himself during the progress of the game, just before the batter strikes. The manager of the team at bat places one 70 of his men on the home plate and throws three dice.

If he shows 1-2-5 or 2-2-6 it is a foul ball. The man at the bat then moves exactly as many squares away from the home 75 plate as the total number shown by the dice, which may be either nine or twelve and he may move in any direction desired outside of the foul line and only on the red squares.

The manager of the team in the field then 80 throws two dice and if the catcher, or any other player indicated by one of the game pieces in the field, can move, according to the number cast by the dice, so that he will stop on the square on which the batter has 85 stopped, moving as many squares on the red squares as the exact number shown by the dice, the batter is out. The man after the batter, who now represents the ball, may move forward a few squares, then move to 90 the left or right and back again or in any desired manner to stop on the ball or catch it with his last jump. If the ball is not caught in this manner, that is if the game piece does not stop on the desired square, 95 the batter strikes again. A fair ball is caught in the same way except that the players move on "fair territory".

If the batter throws three of a kind, that is, 4-4-4, 1-1-1 or 6-6-6 et cetera, it 100 is a home run and any player on the bases completes the circuit and scores a run. If the dice cast show more than thirty points, the ball is considered as being over the fence and a home run is also scored. In this connection it will be noted that the marginal edges of the board, parallel to the foul lines 105 are marked, from 0 to 30, this indicating

the extent of the playing field, and the numbers assisting the players in moving the desired number of squares.

5 If the batter throws 1—1—2 it is "one ball."

If the batter throws 1—1—3 it is a "strike."

Any numbers thrown, excepting those stated, will be fair balls and the batter moves out into the field in any direction he 10 chooses twice as many squares as the total number he has thrown, and takes his position on any square in that row inside of the foul line. The rows are at right angles and every even numbered row is indicated 15 by a figure on the edge of the board and it will be observed that second base is at the intersection of the two rows numbered 20. As an example of the method of playing the game, suppose the batter threw 6—2—2 20 his total number would be ten. This number multiplied by two gives him twenty squares to move away from the home plate and he, therefore, may take his position on any of the red squares in the row between 25 first and second base or on the row between second and third base. If his total were thirty he could take a position on the extreme row of squares near the marginal edge of the board inside of the foul line. 30 Whichever square he selects represents the spot where the ball lands. A total of twenty-four or less is considered a one base hit if not caught. A total of twenty-six or twenty-eight is a two base hit if not 35 caught. A total of thirty is a three base hit if not caught. Three dice are cast by the player representing the team at bat. Two dice are cast by the opponent representing the manager of the team in the field. When 40 the batter has taken his place on the square selected by him in the field, the manager of the team in the field throws two dice and if any one of the men in the field, nearest the batter can stop on the square on which he 45 is located, with the last jump of his move, moving as many square on the red as the exact number shown by the dice, the batter is out. If not, the batter is considered safe, on first, second or third base according to 50 the number thrown as above indicated. The manager of the team at the bat places his men on the bases as the hits are made and another on the home plate to make the next play.

55 Before throwing the three dice for the strike, the manager of the team at bat may give any one of his men on the bases a "lead" off the base by placing him on one of the squares more or less than half way between 60 the bases. If he does this, the manager of the team in the field may throw his two dice to see if his pitcher can catch the man on the base. If the total number thrown by the pitcher as indicated by the dice is an 65 even number, the base runner is considered

out. If it is an uneven number the runner gains the base he happens to be nearest to. If the batter is not put out on first base, all of the other base runners may advance as many bases as he does according to the 70 hit made.

If a batter is caught, the fielder who is moved to stop on the square occupied by the batter, may "put out" the base runner with the same number of jumps he used for the 75 batter, beginning on the square where the batter was caught. If this is accomplished, a double play is considered to have been made.

If, however, there was a man trying to 80 get home from third base, the fielder stopping on the square occupied by the batter may try to stop on the square occupied by the man trying to get home from third instead of on a man running for second or 85 third. This is done by moving the man twice the number of squares he caught the batter with. If he succeeds in this, the batter, and the man running for home would be considered out, making a double play. 90

It will be observed that the system of playing the game closely adheres to that followed in the ordinary outdoor game of base ball and situations like "three out", "bases all occupied" "two out with three on 95 bases" and similar situations occur as often as they would occur in a regular game.

The apparatus may also be employed for playing a game called "catching the burglar."

100

To play this game, the black lines in the center of the board are employed and it will be noted that the square designating the base ball diamond in the above referred to game, is provided with lines dividing the large square into four smaller squares which serve to indicate rooms in a dwelling, and the central spaces represent passage-ways or corridors in the dwelling. The open spaces in the lines represent doors leading into the dwellings and establishing communication between the rooms and corridors. At the extreme corners of the board, relatively large circles are indicated, these representing entrances to the grounds surrounding the dwellings. The black game piece, shown in Fig. 2, is employed to represent the burglar and the game may be played by one or more persons. The different colored game pieces are employed to represent policemen or officers and these are moved according to the spots shown by the dice when cast. 115

The officers take their positions respectively at one of the four gates or corners on the corner of the board which represents the grounds surrounding the house or dwelling. The burglar takes his position in the center of the house on the spot indicated by the numeral 2. The first officer throws 120 125 130

the dice, two being used, and moves toward the house on the red squares only, aiming to enter the house by one of the windows. He may move, however, in any desired direction, moving as many squares as indicated by the dice and the other officers follow in order each casting the dice in turn.

The burglar, represented by the player having the black game piece then casts the dice and after observing the respective positions of the officers moves through the halls or corridors toward one of the door ways leading to one of the four rooms, in this manner seeking to avoid the nearest officer, and thereby attempting to get out of the house in order to make his way toward one of the gates at the corners of the grounds.

As the burglar has four officers against him he is allowed to move twice the number of squares which he throws whenever less than six is thrown. Otherwise he moves the exact number thrown by the dice. No player may jump over another, he must move around him. If any officer should 25 block a window or door, no other player can pass through it, but, he may move as close as possible to the officer blocking the passage-way and if he so desires, choose another route to get near or catch the burglar 30 and gain the full benefit of his throw.

In order to catch the burglar, one of the officers may stop exactly on the square occupied by the burglar, that is, the move indicated by the dice must bring the officer exactly on the square occupied by the burglar. If the officer throws more than is necessary he may move back and forth on two squares until he can stop on the square occupied by the burglar, with his last jump, or he may 40 move in a square or around an officer or around the burglar so long as the current number of moves is made. In the same manner the burglar must jump on one of the squares in the corner of the ground in order 45 to make his "get away" and win.

In passing through the windows or doors leading from the corridors to the rooms of the dwelling, no player is allowed to cross the ends of the walls but must move so as to 50 enter or leave on the only two squares available for that purpose, as a door or window, as will be apparent from a consideration of

Fig. 1. If the burglar should be surrounded by the four officers so that he is unable to move, the officers must throw one dice 55 until one of them throws number 1, thus winning the game or capturing the burglar. This game will be found to be amusing, and if played in accordance with the rules above specified many difficult situations will occur 60 and mental alertness required to win.

The foregoing description and accompanying drawing have reference to what might be considered to be the approved or preferred form of my invention. I desire it 65 to be understood that I may make such changes in the construction, combination and arrangement of parts, materials, dimensions, et cetera, as may prove expedient and fall within the scope of the appended claims. 70

Having thus fully described my invention what I claim as new and desire to secure by Letters Patent, is:

1. A game apparatus comprising a board divided into small squares, and indicated 75 by different colors, a boundary line of a distinguishing color forming a square outline indicating the walls of a dwelling at the center the board, similar lines within the boundary inclosing squares with the corners 80 of said dwelling boundary so as to allow corridors within the dwelling, said lines being broken away so as to allow entrance from the rooms to the corridors and to the exterior of said boundary, and characters 85 marked on the corners of the board and indicating gates for entrances to the grounds surrounding the dwelling, and game pieces indicating a burglar and officers adapted to be moved in the squares of the board. 90

2. A game apparatus comprising a square board having small squares inscribed thereon, and alternately colored in two different colors, a square outlined at the center of said board, squares situated within said first 95 mentioned square so as to have spaces therebetween.

In testimony whereof I affix my signature in presence of two witnesses.
